(57) **CLAIM**

The ornamental design for an oven range, as shown and described.

DESCRIPTION

1. Oven range

1.1 : Perspective

1.2 : Front

1.3 : Back

1.4 : Left

1.5 : Right

1.6 : Top

1.7 : Bottom

1.8 : Reference

Reproduction 1.8 is a reference view showing a state of the front surface glass door changed into the so-called "see-through door" by means of a sensor for detecting approach of and/or contact of person, and forms no part of the claimed design.
